DESIGN FOR A DRESS

David William Price, New York, N. Y.

Application December 3, 1938, Serial No. 81,533

Term of patent 3½ years

To all whom it may concern:

Be it known that David William Price, a citizen of the United States, residing at 1400 Broadway, New York, N. Y., in the county of New York and State of New York, has invented a new, original, and ornamental Design for a Dress, of which the following is a specification, reference being had to the accompanying drawing, forming part thereof.

Fig. 1 is the front view of a dress showing my design, and

Fig. 2 is the rear view of the dress shown in Fig. 1.

I claim:

The ornamental design for a dress, substantially as shown.

DAVID WILLIAM PRICE.
